DESIGN FOR A URINE DEFLECTOR

Samuel M. Bloom, New York, N. Y.

Application July 12, 1944, Serial No. 114,369

Term of patent 3½ years

(Cl. D4—5)

To all whom it may concern:

Be it known that I, Samuel M. Bloom, a citizen of the United States, residing at New York city, in the county of Kings and State of New York, have invented a new, original, and ornamental Design for a Urine Deflector, of which the following is a specification, reference being had to the accompanying drawing, forming a part thereof.

Fig. 1 is a front view of a urine deflector, showing my new design.

Fig. 2 is a top view thereof.

Fig. 3 is a side view thereof.

I claim:

The ornamental design for a urine deflector, substantially as shown.

SAMUEL M. BLOOM.
